UNITED STATES PATENT OFFICE.

REAMER YONG LANE, OF MERIDIAN, MISSISSIPPI.

METALLIC ROD-PACKING.

SPECIFICATION forming part of Letters Patent No. 661,664, dated November 13, 1900.

Application filed July 20, 1899. Serial No. 724,538. (No model.)

To all whom it may concern:

Be it known that I, REAMER YONG LANE, a citizen of the United States, residing at Meridian, in the county of Lauderdale and State 5 of Mississippi, have invented certain new and useful Improvements in Metallic Rod-Pack-
ing; and I do declare the following to be a full, clear, and exact description of the in-
vention, such as will enable others skilled in
10 the art to which it appertains to make and use
the same, reference being had to the accom-
panying drawings, and to the letters of ref-
erence marked thereon, which form a part of
this specification.

15 This invention relates to metallic packing
for piston-rods and the like; and its objects
are, first, to provide a metallic packing of ex-
tremely simple construction which is highly
efficient without a multiplicity of parts and
20 without the necessity of springs or kindred
devices to keep the rings in compression;
secondly, to provide a packing in which the
compression is effected by the steam or other
pressure and is maintained only so long as
25 the pressure is exerted and there is a tendency
for it to escape, whereby unnecessary wear
on all the parts is prevented. I attain these
results by means of the packing hereinafter
described, and as illustrated in the accompa-
30 nyng drawings, in which—

Figure 1 is a longitudinal section of a stuff-
ing-box, showing a portion of a rod and a
half-sectional elevation of my improved pack-
ing applied thereto. Fig. 2 is a sectional end
35 elevation showing the face of the stuffing-
box gland, the inner dotted line showing the
circular section of the packing. Fig. 3 shows
the packing-rings and the compressing-pis-
ton in perspective, somewhat separated. Fig.
40 4 is a half-sectional elevation of a modified
cupped ring.

The interior of the stuffing-box A is cylin-
drical, concentric with the rod B. In its inner
end is received the annular piston C, formed
45 with grooves in its periphery to hold the
spring packing-rings D, which fit snugly into
the bore of the stuffing-box. There should
be a greater amount of friction between the
rings D and the stuffing-box than between
50 the piston and the rod, so that when the steam
or other pressure is removed from the piston

it will not be carried to and fro by the rod,
but will remain stationary in the stuffing-box.

An annular projection C' on the piston C
bears against one or more soft-metal rings 55
surrounding the rod. Two rings are shown in
the drawings, the inner one, E, being substan-
tially cylindrical in form, while the outer one,
E', has a tapering exterior surface, preferably
60 slightly curved, as shown. The rings have
flat abutting ends, and they are split, in order
that they may be closed upon the rod under
pressure. If desired, they may be made in
segments, as indicated by the dotted lines in
Fig. 3. 65

Surrounding the rings E E' is a ring F,
which at its outer end fits the rod and is coun-
tersunk or cupped from its inner end to fit
the outer surface of the rings E E'. The outer
end of the ring F is flat and bears against a 70
similar surface on a ring G, which has a
slightly convex outer end fitting into a con-
cavity in the inner side of the gland H of the
stuffing-box. The usual studs I and nuts K
75 are provided for holding the gland in place. The
ring G may be made integral with the
cupped ring F, if desired, as shown in Fig. 4.

The piston and the several rings are cen-
trally bored to accurately fit the piston-rod,
valve-stem, or other rod B, and a certain 80
clearance is left between their peripheries and
the bore of the stuffing-box, so that the only
parts bearing upon the interior of the box
are the packing-rings D on the piston.

To prevent excessive wear on the packing- 85
rings a washer may be placed behind said an-
nular piston, if desired.

In operation the piston C is forced out-
wardly by the fluid-pressure against the soft-
metal rings E E', compressing them into the 90
cupped ring F, whose tapering interior closes
them upon the rod B. The greater the fluid-
pressure the tighter the rings hug the rods.
When the pressure is relieved, the piston re-
cedes and the rings E E' spring open again. 95
The wear is thus reduced to a minimum.

This device has been used with excellent
results upon both stationary and locomotive
engines.

Having thus described my invention, what 100
I claim is—

The combination with a stuffing-box A and

rod B, of a piston C having an extension C',
rings D on the piston fitting the bore of the
box, packing-rings E E' of soft metal, the lat-
ter having a tapered surface, a cupped ring
5 F fitting the rings E E' and the rod, a ring G
adjacent to the ring F, and a gland H receiv-
ing the ring G.

In testimony whereof I affix my signature
in presence of two witnesses.

REAMER YONG LANE.
